UNITED STATES PATENT OFFICE.

CARL BÜTOW, OF NUREMBERG, GERMANY.

SCREW-PROPELLE.

1,015,540.

Specification of Letters Patent. Patented Jan. 23, 1912.

Application filed June 30, 1911. Serial No. 636,212.

To all whom it may concern:

Be it known that I, CARL BÜTOW, a citizen of the Empire of Germany, residing at Nuremberg, in the Empire of Germany, have 5 invented a new and useful Screw-Propeller, of which the following is a specification.

My invention consists of improvements in screw-propellers, whereby the driving capacity of the propeller is considerably increased.

One improvement consists in that each blade of the propeller partially compasses the nave. Thereby the connection between blade and nave is greatly strengthened.

Another improvement consists in that the two furcate portions of each blade near the nave are helically wound and conically disposed on the nave, so that two cone-like members are formed at the ends of the nave.

The new screw-propeller may be employed in connection with a ventilator or for driving water-ships or dirigible balloons, aeroplanes and the like.

I will now proceed to describe my invention with reference to the accompanying drawings, in which—

Figure 1 is a rear end elevation of a screw-propeller designed for ships, Fig. 2 is a top plan view of the same, Fig. 3 is a side view of the same, Fig. 4 shows the active surface of one blade of the propeller spread in a plane or prior to being fitted to the nave, Fig. 5 is a plan view of a slightly modified form of screw-propeller, Fig. 6 illustrates 35 the same viewed at right angles to Fig. 5, Fig. 7 is an end elevation view of the same, and Fig. 8 shows the active surface of one blade of a screw-propeller for aeroplanes and the like spread in a plane similar to 40 Fig. 4.

Similar characters of reference designate similar parts throughout the several views.

The propeller comprises a cylindrical nave 1 and two blades 2, 2, which, as in Fig. 1, are 45 elliptic or oval and each blade partly encompasses the nave 1. The inclined blades 2, 2 are practically plane from the outer end 50 to the central plane of the nave 1 passing through the line $a-b$ in Fig. 1. From the central plane indicated by the line $a-b$ the inner bifurcated end portions of each blade 2 are conically wound, as is indicated by the radial lines in Fig. 1 and by the shading in Figs. 2 and 3.

55 As is best seen from Fig. 2, each furcation

or end portion 3 of either blade 2 forms a sort of cone upon the nave, the two cones tapering inward. After the blade 2 is blanked out and before its surface is curved, it presents a plane figure like or similar to that 60 which is shown in Fig. 4, being substantially oval in contour and having one end bifurcated, the inner edge 3' of the furcate portion or winding member, having a substantially oval curvature. These inner edges, 65 when fitted to the nave, on a helical line, are inclined to the axis of said nave in such relation that the inclination varies at each successive radial line of the nave. When improved screw-propeller rotates it produces, 70 with its front "cone", a sucking effect, whereby the water near the nave is drawn inward and on leaving the "cone" it is forced under the active plane surface 2 and on entering the rear "cone" the water will 75 be pushed outward.

The modified form of screw-propeller, illustrated in Figs. 5 to 7 inclusive is similar to the one described, and differs therefrom in that each blade 5 is not plane. Its peripheral outer portion from i through j to k in Fig. 7, forms a winding surface as in ordinary screw-propellers the points i and k lying in the maximum width of the blade 5. The generatrix of this winding surface is 85 assumed to be approximately at right angles to the axis of the nave 4. From the points i and k to the ends l and m respectively of the winding end portions 6, 6 the generatrix is, on the contrary, gradually more and 90 more inclined outward to the axis of the nave 4, so that a sort of "cone" is formed at each end of the nave 4, as is best seen from Fig. 5.

In Fig. 5, the modified form of screw-propeller differs from the preceding one (Fig. 2) in that the nave 4 is made longer and the two "cones" project from the blades 5, 5. In both forms the two blades are made substantially elliptic in shape in the end views (Figs. 1 and 7). The form shown in Figs. 5 to 7 also differ from the first described propeller, shown at Figs. 1 to 3, in that the ends of the winding end portions 6, 6, of the respective blades terminate at 100 diametrically opposed points, on the nave, as shown in Fig. 7. I desire it to be expressly understood, however, that I do not limit myself to any angle, between which each winding end portion of any blade lies. The nave, 105 110

which hitherto has been assumed to be perfectly cylindrical, may have any proper shape, as in ordinary screw-propellers.

For aeroplanes, navigable balloons and the like the blades of the improved screw-propeller will require to be made longer, as for example, shown at Fig. 8, where a plane blade with its winding end portions spread in a plane is drawn. Of course also for aeroplanes and the like the blades of the improved screw-propeller may be shaped in any proper manner, the essential point being, that the winding end portions of the blade be conically wound around the nave 15 as described.

For motors of aeroplanes and the like coupled with screw-propellers this improved screw-propeller presents the advantage, that the current of air expelled from the rear 20 "cone" will effectively cool the motor.

The new screw-propeller may be equally well employed in toys and models.

I claim:

1. A propeller-blade comprising a sheet of flat material having its lesser end bifurcated, each furcation of said sheet being gradually tapered to a point, and inclosing an aperture of substantially oval shape, the said furcations being adapted to be secured to the nave 25 of a propeller in such relation that while the greater portion of the sheet of material stands perpendicularly to the axis of the nave the pointed end surfaces of the furcations are on planes parallel to said axis.

2. A propeller, each blade of which when spread upon a plane has one end bifurcated and incloses an aperture of substantially oval shape, both furcations of each blade being tapered to a point and adapted to be secured to the nave in such a manner that the 40 plane of the furcations is gradually more and more inclined toward the nave and the points of the said furcations lie flat on the nave.

3. A propeller with two or more blades, 45 each blade of which when spread upon a plane has one end bifurcated so as to inclose an aperture of substantially oval shape, each of the furcations being tapered to a point and adapted to be secured to the nave in 50 such a manner that the furcations are more and more inclined toward the nave and the points of the said furcations lie flat on the nave.

4. A propeller with two or more blades, 55 each of which when spread upon a plane has one end bifurcated and incloses an aperture of substantially oval shape, each furcation of each blade being tapered to a point and adapted to be secured to the nave in such a manner that the generatrix in the middle of 60 each blade and the generatrix in both points of the same blades are at right angles one to another.

CARL BÜTOW.
